ELECTRIC SABRE SAW OR SIMILAR ARTICLE

Robert I. Gresens, Rochester, N.Y., and Max C. Hauenstein, Monroe, and Arthur M. Felske, Westport, Conn., assignors to General Electric Company, a corporation of New York

Filed June 30, 1966, Ser. No. 2,874

Term of patent 14 years

(Cl. D93—3)

FIG. 1

FIG. 2

FIG. 3

FIG. 4

FIG. 5

FIG. 1 is a front and side perspective view of an electric sabre saw or similar article embodying my new design;

FIG. 2 is a top plan view thereof;

FIG. 3 is a rear and side perspective view thereof;

FIG. 4 is a bottom plan view thereof; and

FIG. 5 is a side elevational view thereof.

The dominant features of the design reside in the portions shown in full lines.

We claim:

The ornamental design for an electric sabre saw or similar article, substantially as shown and described.
